US00D695077S

(12) **United States Design Patent**
Chase

(10) **Patent No.:** **US D695,077 S**
(45) **Date of Patent:** **** Dec. 10, 2013**

(54) **COMPARTMENTALIZED CONTAINER**

(71) Applicant: **Target Brands, Inc.**, Minneapolis, MN (US)

(72) Inventor: **Mark Robert Chase**, Minneapolis, MN (US)

(73) Assignee: **Target Brands, Inc.**, Minneapolis, MN (US)

(**) Term: **14 Years**

(21) Appl. No.: **29/449,032**

(22) Filed: **Mar. 14, 2013**

(51) **LOC (9) Cl.** 07-01

(52) **U.S. Cl.**

USPC **D7/555**

(58) **Field of Classification Search**

USPC D7/555, 584, 557, 553.8, 558, 601, 602, D7/543, 545, 357, 354, 503, 587, 588, 500, D7/396.4, 505, 704, 360, 361, 552.1, 586, D7/562, 560, 566, 504, 565, 553.1, 553.7, D7/549; D9/424, 759, 432, 744, 643, 707; 219/735, 732; 426/243; 220/574, 751, 220/23.4; D1/122; D30/130; 215/382, 400; 206/217

(57) **CLAIM**

The ornamental design for a compartmentalized container, as shown and described.

DESCRIPTION

FIG. 1 is a front, top perspective view of a compartmentalized container showing a first embodiment of our new design; FIG. 2 is a front view thereof, the rear view being identical to front view;

FIG. 3 is a right side view thereof, the left side view being identical to the right side view;

FIG. 4 is a top view thereof; and

FIG. 5 is a bottom view thereof.

FIG. 6 is an exploded front, top perspective view of a compartmentalized container showing a second embodiment of our new design;

FIG. 7 is a non-exploded front, top perspective view thereof; FIG. 8 is a front view thereof, the rear view being identical to the front side view;

FIG. 9 is a right side view thereof, the left side view being identical to the right side view;

FIG. 10 is a top view thereof; and

FIG. 11 is a bottom view thereof.

FIG. 12 is an exploded front, top perspective view of a compartmentalized container showing a third embodiment of our new design;

FIG. 13 is a non-exploded front, top perspective view thereof; FIG. 14 is a front view thereof;

FIG. 15 is a rear view thereof;

FIG. 16 is a right side view thereof;

FIG. 17 is a left side view thereof;

FIG. 18 is a top view thereof; and,

FIG. 19 is a bottom view thereof.

The features shown in broken lines are environmental subject matter to the compartmentalized container or portions of the compartmentalized container forming no part of the claimed design.
